UNITED STATES PATENT OFFICE.

FREDERICK H. JOHNSON, OF SOUTH PASADENA, CALIFORNIA.

CUSHION FOR SPRINKLER HEADS.

Application filed August 5, 1926. Serial No. 127,238.

This invention relates to cushions for sprinkler heads, and is more particularly directed to an attachment for sprinkler heads constructed of a material softer than the sprinkler head and which is adapted for use on athletic fields, parks, and the like.

In the maintenance of turf fields where athletic games, such as football, baseball, golf, and the like, are played, the turf requires a relatively large amount of water, which it has been found can most efficiently be supplied by means of a sprinkler system permanently mounted in position on the field. These athletic fields are subject to great wear, and to install sprinkler heads for giving the same the desired or required amount of water, it has been found that exposing the metal heads at the surface of the turf, that in playing football, or like games, the player is apt to be seriously injured thereby. It is, therefore, an object of this invention to provide a cushion attachment for the sprinkler heads which is constructed of relatively soft material which will protect the player from the metal heads.

Another object of this invention is to provide a cushion for sprinkler heads adapted to cover the top of the sprinkler head and having an orifice formed therein corresponding to the sprinkler head orifice.

Another object of this invention is to provide a cushion attachment for sprinkler heads which is adapted to be mounted on the top of the sprinkler head and which has a beaded portion of less diameter than the rim of the sprinkler head.

Other objects and advantages of this invention will be apparent from the following detailed description of a preferred embodiment thereof, as illustrated in the accompanying drawings.

In the drawings:

Figure 1 diagrammatically illustrates the positioning of sprinkler heads having cushion attachments embodying this invention mounted in position in an athletic field.

Figure 2 is a top plan view of the cushion attachment for sprinkler heads embodying this invention.

Figure 3 is a side elevation thereof.

Figure 4 is a central sectional side elevation of a cushion attachment embodying this invention.

Figure 5 is a perspective view thereof.

In the preferred embodiment of this invention, illustrated in the accompanying

drawings, 1 illustrates an athletic field, which is herein illustrated as of the type employed in playing football, and on which field sprinkler heads 2 are mounted in staggered relation on approximately 12 ft. centers throughout the entire area of the field, and are connected with any suitable or desirable source of water pressure and controlled preferably by an automatic sprinkler system such, for example, as is illustrated in my copending application for control system, Serial No. 65,343, filed October 28, 1925.

The sprinkler heads 2 are of any desired or preferred construction and are herein illustrated as comprising a body 3 having a rim 4 formed at their upper end. A central orifice 5 is formed through the body 3.

The cushion 6 embodying this invention is preferably formed of a soft material such, for example, as vulcanized rubber or the like and in the form herein illustrated has a downwardly extending circumferential flange 7 of less interior diameter than the rim 4 and the sprinkler head 2 is adapted to fit over the rim 4 of the body 2, and in which flange 7 a circumferential groove 8 is formed, into which the rim 4 is adapted to fit. The cushion 6 has an opening or orifice 9 formed in the center thereof or formed in position to correspond with the orifice 5 formed in the body 2.

The cushion 6, as illustrated in the drawing, comprises a tapered inner surface 10, tapering outwardly from the orifice 9, the material of which the cushion 6 is formed terminating at substantially an edge, as illustrated at 11, over the orifice 5 of the body 2 so as to prevent the passage of water into the interior of the cushion 6. The cushion 6 is cut away at a circumferential groove 12 on the interior thereof so that the edge 11 will engage the top surface of the body 3 of the sprinkler head 2.

In forming the cushion 6 for use on fairways of golf courses, the body of the cushion 6 would preferably be formed straight across, eliminating the tapered surface 10 so as to prevent the lodging of the golf ball therein. The cushion 6 when used on golf courses is particularly useful in shielding the sprinkler head 2 from the blows of the golf club so as to save not only the golf clubs but the sprinkler heads.

Having fully described a preferred embodiment of my invention, it is to be under-

stood that I do not wish to be limited to the exact details therein set forth, which may obviously be varied without departing from the spirit of my invention as set forth in the 5 appended claims.

I claim:

1. The combination with a sprinkler head, having a circular flange, of a cushion adapted to be mounted on the sprinkler head, and 10 having a downwardly extending flange for securing the cushion to said sprinkler head flange, the cushion having an axial orifice, and the upper surface of the cushion being flared outwardly from the orifice to permit 15 water to be thrown in a spray directly from the orifice of the sprinkler head.
2. The combination with a sprinkler head, having a circular flange, and an axial orifice, 20 of a cushion mounted on the top of the sprinkler head and having a downwardly extending flange, and a circumferentially extending groove receiving said sprinkler head flange, the cushion having an axial bore and being flared on the top surface outwardly from the axial bore. 25

3. The combination with a sprinkler head having a discharge opening and an outwardly extending flange, of a cushion formed of flexible material adapted to be mounted on top of the sprinkler head and having a 30 downwardly extending flange and a circumferentially extending groove receiving said sprinkler head flange, and the cushion having an axial bore in register with the discharge opening of the sprinkler head. 35

4. The combination with a sprinkler head having an outwardly extending flange and a discharge opening of a cushion including a body of rubber comprising a top disc extending over the top of the sprinkler head and having a bore through which water passing through the discharge opening of the sprinkler head may pass, and a downwardly extending flange having an inner peripheral groove or recess into which the sprinkler head flange is fitted. 40 45

Signed at Los Angeles, Calif., this 31st day of July, 1926.

FREDERICK H. JOHNSON.
